SPARK PLUG

Lloyd McKinsey Field, New London, Ohio, Floyde Josephine Field Karcher, Pueblo, Colo., executrix of said Lloyd McKinsey Field, deceased, assignor, by mesne assignments, to Andrew R. Cochrane, trustee, Pittsburgh, Pa.

Application May 25, 1951, Serial No. 228,282

4 Claims. (Cl. 123—169)

1

This invention relates to an improved spark plug of the general type in which a valve-controlled passage admits a fluid to the engine cylinder equipped with said plug, upon each intake stroke of the piston.

The plug includes an insulator which for manufacturing advantage is transversely divided into upper and lower abutting sections, said insulator sections having central fluid admission ports. At least one of the insulator sections is formed with a recess communicating with the upper and lower ports and receiving the valve. This valve is in the form of a head on the upper end of a lower central positive electrode section which is reciprocable in the lower port and is cooperable with a negative electrode carried by a metal shell in which the insulator is secured.

When a plug of this type is used in a present-day high-compression engine, the high compression within the cylinder greatly resists the jumping of the spark across the spark gap. Thus, if there be any reduced pressure zone at the inner side of the shell into which any compressed gas may flow between the abutting insulator sections, the resistance to jumping of the high tension current to said shell will be less along such a path of gas flow than across the spark gap, with the result that the plug will short and fail to fire. The use of a sectional insulator in a plug of the type under consideration, therefore, presents the problem of effectively preventing any compressed gas travel from the valve-containing chamber to the shell between the insulator sections.

It is the principal object of the present invention to solve the above problem in a simple yet effective way, by providing an improved construction in which the zone of contact of the abutting insulator sections, is subjected at both its inner and outer peripheries to the compression within the cylinder. By thus equalizing the pressure at the inner and outer peripheries of the zone of contact of the insulator sections and the pressure to which the spark gap is subjected, there will be no compressed gas flow between the insulator sections, no reduced pressure zone at the inner side of the shell, and no path of possible current travel having less resistance than the spark gap, with the result that the plug will effectively fire.

In carrying out the above end, a further object is to make extremely simple provision whereby the compressed gas in the cylinder may reach both the inner and outer peripheries of the zone of contact of the insulator sections.

Another object of the invention is to provide a novel construction in which it is only necessary to provide a compression seal between the upper insulator section and the metal shell.

A still further object is to make novel provision

5 for conducting the high tension current from the upper to the lower section of the central positive electrode.

Yet another object is to provide a novel construction which may be expeditiously manufactured and profitably marketed at a reasonable price.

With the above and other objects in view that will become apparent as the nature of the invention is better understood, the same consists in the novel form, combination and arrangement of parts hereinafter more fully described, shown in the accompanying drawing, and claimed.

In the drawing:

Figure 1 is a longitudinal sectional view of a spark plug embodying the improvements,

Figure 2 is a lower end view of the upper insulator section, and

Figure 3 is an upper end view of the lower insulator section.

In the drawing, a construction has been shown which is well adapted to the attainment of the desired ends, and while this construction will be rather specifically described, it is to be understood that variations may be made within the scope of the invention.

A metal shell 5 is provided having a threaded lower end 6 for reception in the usual spark plug opening of an internal combustion engine cylinder head. The side wall 7 of the shell 5 has a relatively large internal diameter 8 at its upper end, a small diameter 9 between its ends, and a still smaller diameter 10 at its lower end. This construction provides an upper inverted frusto-conical bore 11 and a lower inverted frusto-conical bore 12 in the shell. The upper end of the shell carries an insulator-clamping ring nut 13 and the lower end of said shell is provided with a suitable negative electrode 14.

The insulator comprises an elongated upper section 15 and a relatively short lower section 16. The upper section 15 is provided with an inverted frusto-conical lower end 17 seated upon the air seal 18 engaging the upper bore 11 and is held tightly in place by the ring nut 13. The lower section 16 is formed with an inverted frusto-conical portion forming a shoulder 19 engaging the bore 12 but no attempt is made to provide a gas-tight engagement of said shoulder 19 with said bore 12. In fact, flow of gas is purposely allowed between the contacting surfaces of said insulator section 16 and said bore. A gas passage to permit this flow between the shoulder 19 and bore 12, may be provided by allowing tolerances in manufacture, to give a not-too-accurate fit between said shoulder and bore, or other provision could well be made for attaining the desired end. The presence of a sufficiently imperfect fit to provide the gas passage is represented in the drawing by the heavy lines 20.

Above the bore 12, the insulator section 16 has clearance 21 with the diameter 9 of the shell wall 7, and the upper end of said section 16 may be reduced at its outer periphery to provide a distinct circular chamber 22. Compressed gas from the engine cylinder reaches this chamber 22 through the passages 20 and 21 upon each compression stroke of the piston, for a purpose to appear.

The insulator sections 15 and 16 have abutting inner ends 24 and 25 respectively, and no attempt to have these inner abutting ends fit each other in a gas-tight manner is necessary. The upper insulator section 15 is formed with a central fluid port 26 from end to end. The lower section 16 is provided with a recess 27 in its upper end, and also has a port 28 from said recess 27 to its lower end. The bottom of this recess 27 is formed with grooves 29 radiating from the port 28.

A lower, reciprocable, central, positive electrode section 30 is loosely received in the port 28, the lower end of said electrode section 30 being laterally spaced from the inner end of the negative electrode 14. The upper end of the electrode section 30 is provided with a suitable valve head 31 loosely received in the recess 27, to engage the seat 32 which is a part of the insulator section 15, upon each compression stroke of the piston. Upon each intake stroke, the electrode section 30 and the valve head 31 lower, thereby admitting fluid through the port 26, recess 27, and port 28. The grooves 29 prevent the valve head 31 from closing the upper end of the port 28 when said valve head is lowered.

An upper tubular electrode section 33 is suitably secured in the upper end of the port 26 and has a binding post portion 34 for connection with a spark plug wire. A wire conductor 35 establishes electrical communication between the upper electrode section 33 and the lower electrode section 30.

Upon each intake stroke of the piston within a cylinder equipped with the improved spark plug, fluid enters the cylinder through the tubular upper electrode section 33, port 26, recess 27, grooves 29 and port 28. Upon each compression stroke the valve head 31 is forced upwardly and seats against the seat 32, preventing loss of compression. Also, during each compression stroke, compressed gas enters the recess 27 through the port 28 and enters the chamber 22 through the passages 20 and 21. Thus, the pressure at the inner and outer peripheries of the contacting surfaces 24 and 25 of the insulator sections and the pressure to which the spark gap is subjected, is equalized. The result is that the high tension current cannot jump from the central electrode to the shell wall 7 with less resistance than it can jump the spark gap. Consequently, the plug will effectively fire regardless of the fact that no seal is provided between the surfaces 24 and 25.

While there is herein shown and described the preferred embodiment of the invention, it is nevertheless to be understood that minor changes may be made therein without departing from the spirit and scope of the invention as claimed.

I claim:

1. A spark plug comprising a shell having grounding means, an insulator divided into an upper section and a lower section, said insulator sections having abutting ends within said shell, the inner end of at least one of said insulator sections having an internal recess, said upper insulator section having a fluid port extending

to said recess, said lower insulator section having a central port extending from said recess to the lower end of said lower section, the inner periphery of the zone of contact of said abutting insulator sections being subjected to gas pressure entering said recess through said lower port during engine operation, gas-conducting means extending to the outer periphery of said zone of contact and open toward the lower end of the plug for subjecting said outer periphery to the same gas pressure as said inner periphery, means fixedly mounting said insulator sections in said shell, said mounting means including inclined contacting surfaces between said upper insulator section and said shell, said contacting surfaces being above the aforesaid zone of contact between the insulator sections, a central positive electrode section loosely reciprocable in said lower port and having a valve head in the aforesaid recess to close said upper port when raised, and means for conducting current to said central electrode section.

2. A structure as specified in claim 1; said mounting means for said insulator sections including an upwardly facing inverted frusto-conical bore in said shell and an inverted frusto-conical shoulder on said lower insulator section, said shoulder and bore having such engagement as to provide a gas passage between them, said gas passage forming a portion of said gas-conducting means, said lower insulator section having clearance with said shell from said gas passage to the upper end of said lower insulator section, said clearance forming another portion of said gas-conducting means.

3. A structure as specified in claim 1; said mounting means for said insulator sections including an upwardly facing inverted frusto-conical bore in said shell and an inverted frusto-conical shoulder on said lower insulator section, said shoulder and bore having such engagement as to provide a gas passage between them, said gas passage forming a portion of said gas-conducting means, said lower insulator section having clearance with said shell from said gas passage to the upper end of said lower insulator section, said clearance forming another portion of said gas-conducting means, said upper end of said lower insulator section having a reduced diameter providing a circular chamber around the aforesaid zone of contact, said chamber completing said gas-conducting means.

4. A structure as specified in claim 1, the inner end of one of said insulator sections being of reduced diameter to provide a circular chamber around said outer periphery of said zone of contact, said chamber forming a portion of said gas-conducting means, the upper extremity of said lower insulator section being of reduced diameter to provide a circular chamber around said outer periphery of said zone of contact, said chamber forming a portion of said gas-conducting means.

LLOYD MCKINSEY FIELD.
